UNITED STATES PATENT OFFICE.

WILLIAM R. MORRIS, OF KINGSLAND, ARKANSAS.

GATE-LATCH.

No. 826,952.

Specification of Letters Patent.

Patented July 24, 1906.

Application filed July 6, 1905. Serial No. 268,832.

To all whom it may concern:

Be it known that I, WILLIAM R. MORRIS, a citizen of the United States, residing at Kingsland, in the county of Cleveland and State of Arkansas, have invented certain new and useful Improvements in Gate-Latches; and I do declare the following to be a full, clear, and exact description of the invention, such as will enable others skilled in the art to 10 which it appertains to make and use the same.

My invention relates to improvements in gate-latches; and it consists in the novel construction, combination, and arrangement of 15 devices hereinafter described and claimed.

The object of the invention is to provide a simple, durable, and efficient latch of this character which will automatically adjust itself as the gate sags, so that it will always 20 engage the keeper upon the gate-post.

The above and other objects, which will appear as the nature of my invention is better understood, are accomplished by means 25 of the construction illustrated in the accompanying drawings, in which—

Figure 1 is a side elevation of a portion of a gate and a gate-post, showing my improved latch applied thereto. Fig. 2 is a vertical sectional view taken on the line 2 2 in Fig. 1. 30 Fig. 3 is a horizontal sectional view taken on the line 3 3 in Fig. 1. Fig. 4 is a vertical sectional view through the latch. Fig. 5 is a perspective view of the latch proper and its adjusting-plate. Fig. 6 is a rear elevation of 35 the adjusting-plate of the latch, and Fig. 7 is a perspective view of the latch-keeper.

Referring to the drawings by numeral, 1 denotes a portion of a swinging gate, 2 a gate-post serving as a stop for the free end of the 40 gate, and 3 my improved latch. The latch comprises a base or guide plate 4, which is substantially rectangular in form and secured upon the gate 1 by screws or the like 5, which are passed through apertures in the ends of 45 said plate. The latter has its inner face recessed, as shown at 6, and in its outer face is formed a centrally-disposed longitudinally-extending slot 7. Slidably mounted in the recess 6 and slot 7 is an adjusting plate or element 8, which carries the swinging latch proper, 9. Said plate or element 8 consists 50 of a substantially rectangular base portion which is adapted to slide in the recess 6, and formed upon the outer face of said portion 8 is an enlargement 10, which projects through 55 and slides in the slot 7. Said enlargement

10 has at its lower portion a projecting arm 11, which is slightly tapered, as shown, and in its upper portion is formed a slot or opening 12, through which the latch 9 extends. 60 Said latch has at its outer end a hook 13 and a finger-piece 14 and at its inner end two oppositely-projecting pivot studs or lugs 15, which engage bearing-recesses 16, formed on the inner face of the base portion of the adjusting-plate 8. The latch 9 is also formed at its inner end with a shoulder 17, which is held normally in engagement with the lower end of the slot 12 by a coil-spring 18, which is retained between projections 19 upon the 70 plate 8 and the latch 9, and which tends to force said latch downwardly toward the arm 11. The pivot studs or trunnions 15 of the latch 9 are retained in the recesses 16, and the adjusting-plate 8 is forced into frictional 75 engagement with the recessed portions 6 of the guide-plate 4 by a plate-spring 20, which is disposed in a longitudinally-extending recess 21, formed at the rear of the base portion of the plate 8, as clearly shown in Fig. 4 of 80 the drawings. This plate-spring 20 is slightly bowed and has its central portion bearing against the gate 1 and the pivoted end of the latch and its ends seated in the recess 21, so that the slidable adjusting-plate 8 will be 85 held against movement in the guide-plate 4 by the frictional contact of said plates. In order to render this contact more effective, the opposing faces of the lower end of the plate 8 and the recess 6 of the plate 4 are 90 formed with coacting serrations 22, as clearly shown in the drawings. These serrations 22 may be of any desired form that will cause the spring 20 to hold the sliding plate 8 firmly in position and at the same time permitting 95 it to slide in either direction when said plate 8 is moved longitudinally. The spring 20 by bearing against the pivoted inner end of the latch keeps the trunnions of the latter in the recesses 16 and also prevents the latch from 100 wearing the gate.

Upon the gate-post 2 is provided a keeper 23, which consists of a base-plate 24, formed with apertures to receive screws or the like 25, which secure said plate to the post. Upon 105 the outer face of the plate 24 are formed two V-shaped projections 26 and 27, which are spaced apart, as shown. The hook 13 of the latch 9 is adapted to coact with the upper portion of the projection 26, as clearly shown 110 in Figs. 1 and 2 of the drawings, and the tapered arm 11, upon the sliding latch-carrying

plate 8, is adapted to coact with the adjacent portion of both of the projections 26 27, so as to guide the latch 9 into engagement with the upper projection 26. It will be seen that as the gate is swung to its closed position the arm 11 will enter between the projections 26 27 and the latch 9 will ride over the upper portion of the upper projection 26 until its hook 13 drops in rear of the same. Should the gate sag or the keeper not be in the proper plane, so that the arm 11 strikes either of the adjacent faces of the projections 26 27, it will be seen that the plate 8 will be slid either upwardly or downwardly until the said arm enters between said projection. The latch thus automatically adjusts itself upon the gate, so that it will always engage the keeper when the gate is swung to its closed position.

Having thus described my invention, what I claim as new, and desire to secure by Letters Patent, is—

The herein-described gate-latch comprising the keeper having spaced V-shaped lugs, in combination with the slotted guide-plate having a recessed inner face, an adjusting-plate slidably mounted in the slotted and re-

cessed portions of the guide-plate, the opposite faces of said guide and adjusting plates having coengaging serrations, and said adjusting-plate being recessed on its inner side and having a tapered arm on its outer side to enter the space between the lugs of the keeper, and being further provided with a slot above said tapered arm, a latch having its inner end in the said slot, provided at its extreme inner end with bearing-trunnions engaging the recesses in the adjusting-plate on opposite sides of the slot, said latch being further provided with a shoulder to engage the inner end of the tapered arm, and a flat spring 20 in the recess in the inner side of the adjusting-plate and with its intermediate portion bearing against the pivoted inner end of the latch and adapted to bear against the surface against which the guide-plate is secured, substantially as described.

In testimony whereof I have hereunto set my hand in presence of two subscribing witnesses.

WILLIAM R. MORRIS.
